[57] CLAIM

The ornamental design for a helmet face shield mounting bracket, as shown and described.

DESCRIPTION

FIG. 1 is a perspective view of a helmet face shield mounting bracket showing my new design; the helmet and face shield depicted in broken lines for illustrative purposes only;

FIG. 2 is an enlarged front elevational view of the helmet face shield mounting bracket of FIG. 1;

FIG. 3 is a top plan view thereof;

FIG. 4 is a rear elevational view thereof;

FIG. 5 is a bottom plan view of FIG. 4; and

FIG. 6 is a left side elevational view of FIG. 2.
The right hand bracket is a mirror image of the left hand holder, except for the letter "R".
